UNITED STATES PATENT OFFICE.

WILLIAM TERRY, OF PEARL CITY, ILLINOIS.

HORSE-COLLAR FASTENER.

No. 892,331.

Specification of Letters Patent.

Patented June 30, 1908.

Application filed February 21, 1908. Serial No. 417,121.

To all whom it may concern:

Be it known that I, WILLIAM TERRY, residing at Pearl City, in the county of Stephenson and State of Illinois, have invented a new 5 and Improved Horse-Collar Fastener, of which the following is a specification.

This invention, which relates to means for securing the upper ends of horse collars, more especially has for its object to provide an improved 10 construction of such means of that type in which two opposing interlocking plates are provided, and my said invention comprehends certain details of construction and novel combination of parts, hereinafter 15 fully described and specifically pointed out in the claims.

Horse collar fasteners of the type referred to usually include a latch lever mounted on one of the interlocking members and held 20 spring pressed to its locking position, and for coöperating with a latch member mounted on the other locking member that snaps into a locked engagement with the latch lever when the two opposing members of the fastener 25 are brought together.

In the practical use of the spring closed latch levers, especially in cold weather, they are sometimes difficult to quickly and properly adjust, by reason of the arrangement of 30 the springs that coöperate with the levers.

My invention more especially has for its object to provide an improved construction of latch device and a spring that coöperates therewith, whereby the lever can be entirely 35 released of the spring pressure so it can be easily, practically and instantly moved entirely out of engagement with the latch so the same can be positively engaged therefrom, means being also provided for preventing a 40 too far throw of the latch lever when released from the latch lug.

Referring now to the accompanying drawings, Figure 1, is a perspective view of the fastener, the two parts being shown as firmly 45 locked together. Fig. 2, is a similar view and shows the manner in which the spring held lever is adjusted for releasing the latch lug. Fig. 3, is a horizontal section of my improved fastener, taken substantially on the line 3—3 50 on Fig. 1. Fig. 4, is a detail perspective view of one end of one of the fastening members and the adjustable binder plate that coöperates therewith.

In the practical construction, my improved 55 collar fastener comprises a pair of opposing curved plates 1—2, adapted for

being secured to the upper ends of the two members of a horse collar respectively, and each of the said plates has a pair of outwardly extended arms 10—20, each of said arms being formed with a longitudinal slot 11 and a series of apertures 12, the latter being provided for receiving the sets of projections 31 on the inner ends of the binder plates 30—30 that are clamped upon the arms 10—20 by screw bolts 4 and nuts 4^a, the bolts passing through the slots 11—11 and the plates 30 and made fast by the nuts as shown, such arrangement of parts providing for adjustably mounting the binder plates 30 and holding the same firmly to their adjusted positions.

The adjacent or inner ends of the plates 1 and 2 have angle portions that form face plates 13—23, one of the said plates 23 being horizontally slotted as at 23^a for the passage therethrough of the latch lug 13^a integral with the plate 13, the said lug having the usual tapered face and locking shoulder as shown.

3 designates a latch lever that is fulcrumed near one end upon a pivot bolt 5 on the plate 23 and which extends to the other end of the said plate 23 and terminates in a head portion having a segmental slot 33 for riding 85 on a headed stud bolt 24 projected from the plate 23 that serves to hold the lever from lateral or twist strain as also for limiting the outward swing of the lever when it is adjusted to the latch releasing position, as 90 shown in Fig. 2. It will be noticed that the lever 3 is mounted on the face plate 23 in such manner that its lower edge normally projects over the slot 23^a so as to be engaged by the bevel face of the latch member when it 95 is forced through the said slot 23 so as to drop back into the locked engagement with the said latch when its locking shoulder projects beyond the said lever 3. The lever 3 is normally held to its locking position by spring 100 pressure and it has a flat lateral extension 34 with which engages the free end 40 of a flat spring 41, the inner or foot portion 41^a of which is riveted to the plate 2 in such manner that the outer or free end can be readily bent 105 back from under the extension 34, which extension, as is clearly shown, is located adjacent the pivoted end of the lever.

By arranging the spring 4 as shown and described, the same can be readily moved from 110 under the lever, see Fig. 2, so as to permit the said lever being freely swung out of engage-

ment with the latch, since it is then entirely free of spring resistance, thus making it easy to manipulate with gloved hands and also to hold the lever to its outwardly swung position during the manipulation of adjusting the two plates, since the springs can be held to bear against the end of the lever to act as a brake for holding the said lever from freely dropping down to its locked position, it being obvious that by pressing the spring in the outward direction the latch will drop to its locked position, when, by releasing the pressure on the free end of the spring, the said end will swing back under the extension and firmly hold the latch to its locked position.

Having thus described my invention, what I claim and desire to secure by Letters Patent, is:—

1. A horse collar fastener that comprises two members having opposing face plates, one of the face plates being slotted, the other having a latch member for projecting through the slot, a locking lever pivotally mounted on the slotted face plate, a spring for normally

forcing the inner edge of the lever into the slot in the latch member, the front end of the lever having a segmental slot and a headed stud on the face plate that coöperates with the slotted end of the lever, substantially as shown and described.

2. The combination of the two opposing members having face plates, one of the face plates being slotted, the other having latch lug for projecting through said slot; of a lever fulcrumed near one end of the slotted face plate, the pivoted end thereof having a lateral extension, the other end having a slotted head, a stud on the face plate for engaging the slotted head and a flat spring having a foot portion secured adjacent the pivot end of the lever and having its front end normally projected under said lever and adapted to be bent back from engagement with the lateral extension of the lever, for the purposes set forth.

WILLIAM TERRY.
